UNITED STATES PATENT OFFICE.

WILLIAM S. E. SEVEY, OF NEW ORLEANS, LOUISIANA.

FENDER.

No. 825,871.

Specification of Letters Patent.

Patented July 10, 1906.

Application filed May 5, 1906. Serial No. 815,332.

To all whom it may concern:

Be it known that I, WILLIAM S. E. SEVEY, a citizen of the United States, residing at New Orleans, in the parish of Orleans and 5 State of Louisiana, have invented new and useful Improvements in Fenders, of which the following is a specification.

My invention pertains to fenders for use on street-railway cars; and it contemplates the 10 provision of fenders adapted to be permanently applied to the front and rear ends of a car and constructed with a view of normally resting in a raised position against the dashboards, where they will be out of the way and 15 not liable to cause accidents and of being expeditiously lowered when necessity demands, so as to pick up a person in the way of the car and effectually preclude the possibility of such person getting under the car-wheels. 20 Other advantageous features of my invention will be fully understood from the following description and claims when the same are read in connection with the accompanying drawings, forming part of this specification, 25 in which—

Figure 1 is a perspective view illustrating a portion of a street-railway car equipped with one of my novel fenders, the vertically-swinging member of the fender being shown 30 in its lower position. Fig. 2 is a detail vertical transverse section showing the swinging member by full lines in its upper position and by dotted lines in its lower position, and Fig. 3 comprises enlarged disconnected perspective views of parts of the fender. 35

Similar letters designate corresponding parts in all of the views of the drawings, referring to which—

A is a portion of the body of a street-railway car, which may be, and preferably is, of the ordinary well-known construction, and B is the main frame of my novel fender. The 40 said frame B comprises side bars *a*, fixedly connected to the sides of the end portion of the body A and having bifurcations *b* in their forward ends, and a cross-bar *c* of circular form in cross-section, having flat end portions *d* let into the bifurcations *b* of the side bars *a* and fixedly connected to the same. 45 About the said cross-bar *c* are coiled springs C, which are connected at their outer ends to the bar and are designed to serve a purpose hereinafter pointed out.

D is the vertically-swinging member of the 50 fender. This member D comprises a frame *e* and a net *f* thereon, and it is provided on the

upper ends of the end frame-bars with eyes *g*, which loosely receive the cross-bar *c* of the main frame B, as best shown in Fig. 1. Said member D is also provided in the upper bar 6c of its frame *e* with apertures *h*, which receive the inner ends of the springs C, and hence it will be apparent that when the member D is swung up the springs C will be placed under tension. 65

E is a vertically-swinging catch fulcrumed at an intermediate point of its length in the dashboard of the car and having a toe *k* at its forward end adapted to engage and hold the member D when said member is swung up 70 against the tension of the springs C.

F is a pedal-lever fulcrumed on the car-platform, and G is a rod interposed between and connecting the pedal-lever and the rear arm of the catch E. By virtue of this construction it will be seen that the member D may be secured in a raised position, as shown by full lines in Fig. 2, where it will be out of the way and will not be liable to give rise to an accident, and it will also be seen that in 80 the event of a person getting on the track in front of the car the motorman is enabled to release the member D by simply pressing the lever F down with his foot. When the member D is thus released, the springs C under 85 tension, as before described, will operate to expeditiously throw the member down and hold it in close proximity to the pavement, so as to assure the member picking the person up. 90

H H are the side guards of the fender. These side guards comprise frames *p*, fixedly connected to the sides of the end portion of the car-body, and nets *r*, connected to, and carried by the said frames, and they are reinforced by braces *s*, interposed between and connected to the bottom of the platform and the lower bars of their frames *p*. 95

As will be observed by reference to Fig. 1, the swinging member D rests when in its lower position snug against the forward ends of the fixed side guards H, and consequently it is impossible for a person to pass the swinging member D at either side thereof and get under the wheels in that way. 100

It will be gathered from the foregoing that when a car is equipped at both ends with my novel fenders the swinging member of the rear fender is always in a raised position, and hence is not liable to catch the dresses of 105 women getting on or off the car or otherwise cause accidents. It will also be gathered

that when it is necessary to couple either end of the car to another car the swinging member of the fender at such end may be expeditiously raised and secured in a raised position.

In addition to the practical advantages which I have hereinbefore ascribed to my novel fender it will be noticed that the same is simple, compact, and inexpensive in construction and embodies no delicate parts such as are liable to get out of order after a short period of use.

Having described my invention, what I claim, and desire to secure by Letters Patent, is—

1. In a fender, the combination of a car-body having a slotted dashboard, a main frame connected to the car-body and having a cross-bar, a vertically-swinging member comprising a frame, pivotally connected to said cross-bar and a net connected to and carried by said frame, one or more coiled springs arranged on and connected at one end to the cross-bar of the main frame and connected at their opposite ends to the vertically-swinging member, a vertically-swinging catch extending through the slot of the dashboard and having a toe on its forward

arm arranged to engage the vertically-swinging member when the same is raised, a pedal-lever mounted on the car-body, and a connection between said pedal-lever and the rear arm of the catch.

2. In a fender, the combination of a car-body having a dashboard, a main frame connected to the car-body and having a cross-bar, side guards fixedly connected to the car-body and said main frame and respectively comprising a frame, and a net carried thereby, a vertically-swinging member comprising a frame pivotally connected to the cross-bar of the main frame and a net carried by the frame, one or more coiled springs arranged on and connected at one end to the cross-bar of the main frame and connected at their opposite ends to the vertically-swinging member, and means on the dashboard for retaining the vertically-swinging member in its raised position.

In testimony whereof I have hereunto set my hand in presence of two subscribing witnesses.

WILLIAM S. E. SEVEY.
